J. F. KELLY

FLOOR AND WALL MOP

Filed Feb. 28, 1922

Patented May 29, 1923.

1,456,696

UNITED STATES PATENT OFFICE.

JOHN FRANCIS KELLY, OF ELMINS, WEST VIRGINIA.

FLOOR AND WALL MOP.

Application filed February 28, 1922. Serial No. 540,052.

To all whom it may concern:

Be it known that I, JOHN F. KELLY, a citizen of the United States, and resident of Elkins, in the county of Randolph and State 5 of West Virginia, have invented certain new and useful Improvements in Floor and Wall Mops, of which the following is a specification.

This invention relates to the class of 10 brushing and scrubbing and more especially to a combined floor and wall mop.

The object of the invention is to provide an improved, novel, simple and efficient mop of the class described adapted to hold a suitable 15 mop head of cloth such as tufted fabric provided with a pile surface, or loose strands doubled upon themselves, and in which provision is made for rinsing the mop in a bucket or other suitable receptacle or for 20 wringing the same, the cloth of the mop being also adapted to be rendered taut or placed under tension when in a position for use or to be released or freed thereof to hang loosely during the wringing or rinsing operation.

A further object of the invention is to provide a novel holder for the mop cloth, together with means for anchoring the ends thereof and for imparting a spiral or revolving motion to one end of the mop cloth 30 whereby the water or cleansing fluid may be wrung or compressed therefrom, novel means being provided for this purpose, while provision is also made for clamping a 35 brush upon the mop holder for use as desired, in conjunction with the mop.

With these and other objects in view, my invention consists in certain peculiarities of 40 construction, novel arrangements and operation of the various parts of the device as will be hereinafter more fully set forth and specifically claimed.

In the drawings,

Figure 1 is a perspective view of the improved floor and wall mop.

Figure 2 is an enlarged fragmentary central vertical sectional view of the lower portion of the mop.

Figure 3 is an enlarged cross sectional view of the nut or slide of the wringing device.

Figure 4 is a central longitudinal sectional view taken along line 4-4 of Figure 3, and

Figure 5 is a fragmentary bottom view of the mop.

Referring to the drawings in detail, in which for purpose of illustration is shown the preferred embodiment of the invention and in which like reference characters designate corresponding parts throughout the several views, my improved combined floor and wall mop is shown as embodying a handle 5, preferably somewhat elongated and of circular cross section, adapted to 60 carry the operating parts of the mop including the mop holder and wringing device to be hereinafter described.

Mounted on the lower threaded portion of the handle is a sleeve 6 threaded or otherwise retained thereon as indicated at 7, the sleeve being shown internally threaded for 65 engaging the externally threaded portion of the handle in the form shown.

Mounted on the lower threaded portion of the handle is a sleeve 6 threaded or otherwise retained thereon as indicated at 7, the sleeve being shown internally threaded for 70 engaging the externally threaded portion of the handle in the form shown.

This sleeve carries the mop holder and for 75 this purpose, there are provided upon opposite sides of the sleeve or attaching member 6, a pair of outwardly and downwardly branching arms 8, the lower portions of which are disposed in substantially parallel 80 relation and are provided with outturned lower extremities 9 forming pivots normally sprung outwardly by reason of the resiliency of the material forming the arms. The arms are preferably formed of resilient 85 or spring steel or other suitable springing material, but they normally spring apart, said parts being also of round stock material as are the parts now to be described.

The mop holder proper consists of a substantially oblong or rectangular frame formed of a strip of material bent intermediate of its ends to form a front or connecting portion 11 and side portions provided with pivot ears 12 engaged by the outwardly directed pivots 9, the ears projecting upwardly from the side portions for this purpose. The inner or rear extremities of the side portions of the frame 10 are directed inwardly toward each other and substantially 90 in alignment in opposite directions, as indicated at 13, these portions being designed to form stops for limiting the pivotal movement upwardly of the adjacent end of the frame. The side portions of the frame 10 are also braced and connected in the relation described through the medium of relatively flat cross strips or braces 14 disposed upon opposite sides of the pivots 9 with respect to the longitudinal dimensions 95 of the frame and the pivot axis thereof.

It is also pointed out that the portion of

the frame 10 projecting rearwardly from the pivot 9 is shorter than the forwardly projecting portion provided with the connecting part or bight 11 so that the frame 5 is overbalanced at the front to provide a preponderance of weight forwardly of the pivots of the frame which causes the frame to swing upwardly at the back and in contact with the arms when in normal position, the 10 inwardly directed portions or stops 13 serving by contact with the arms to limit the said upward swinging movement. It is also pointed out that the cross strips or braces 14 are disposed to project beyond the 15 diameter of the side portions of the frame and at the front portion of the frame slightly spaced in rear of the connecting portion 11 is a cross bar 15, around which the mop cloth proper 16 is folded or extended, as more clearly shown in Figure 2 20 of the drawings. The mop cloth is formed of a strip of tufted or pile fabric, or strands of soft material as commonly used in mops, and in practice is folded on the cross bar 25 15 intermediately of the strips of which the mop cloth is formed and then extended under the cross strips or braces 14 with the rebent portions disposed in contact, and then extended upwardly around the rear cross 30 brace or strip 14, being retained in position between the sides of the frame 10 and held from displacement by the inwardly directed portions 13. The mop cloth is also prevented from shifting laterally when in use, being 35 confined between the sides of the frame both at the front and rear ends of the frame and the active or contacting portion of the mop cloth, when in use.

Projecting rearwardly from the sleeve or 40 attaching member 6 is an apertured guide arm or bearing 17, and mounted on the handle considerably up from the bottom there is a collar 18 having a similar rearwardly projecting guide arm or plate 19 disposed in 45 alignment with the bearing 17, said arms or bearings rotatably receiving the upper and lower extremities of a spiral feed member or screw 20, preferably formed of two inter-twisted wire rods as shown. The screw is 50 supported against longitudinal displacement by a collar 21 fixed to the screw by a set screw or the like 22 in position so that the collar will engage the arm or bearing plate 17, thus preventing the screw from shifting 55 downwardly by its weight. The lower ends of the rods forming the screw are provided with branching portions disposed in outwardly divergent relation as indicated at 23 for supporting or attaching a clamping 60 member consisting of a jaw plate or strip 24 to which said branching ends are rigidly connected and a detachable jaw or plate 25 having a central aperture for engaging a screw shank 26 carried by the jaw 24 where- 65 by the extremities of the strip forming the

mop head 16 engaged on said screw shank, may be clamped between the jaws or plates as clearly shown in Figure 2 of the drawings, a thumb nut or the like 27 being mounted on the screw shank in order to secure the parts in binding relation. 70

In order to impart a revolving motion to the spiral feed screw so as to twist the mop head for the purpose of wringing or rinsing the same, an operating nut in the form of a cylindrical handle 28, is provided, said handle having a longitudinal bore 29 receiving or engaging the feed screw 20 and having oppositely and inwardly directed pins 30 disposed intermediately of the length thereof and opposing each other in the grooves of the spiral screw 20 at their tapered ends 31, so that when the rear end of the frame 10 is swung upwardly against the arms 8, the operator by grasping the handle 28 and moving the same downwardly over the screw, will impart a revolving motion thereto, so as to twist the free end of the mop cloth, while the opposite end is held or restrained by the cross bar 15, thus twisting the free end of the mop cloth, and wringing the same to expel or compress the water or other washing fluid therefrom, or for the purpose of conveniently rinsing the mop in a bucket or other suitable receptacle, it being observed in this connection that the mop holder proper is folded and occupies but a small amount of space in this position. On shifting the nut or handle in the opposite direction so as to move upwardly on the spiral screw, reverse motion is imparted thereto and thus to the free end of the mop cloth so that the latter is then untwisted and permitted to assume its working position. When the mop is in use for mopping floors or walls, pressure downwardly above the handle while the forward end of the mop is in contact with the surface to be cleaned, will render the mop cloth taut as clearly shown in Figures 1 and 2 of the drawings, the strip being placed under tension around the brace or cross strip 14 near the rear end of the frame and between the side portions thereof, while being also held from displacement by the inwardly directed extremities 13 forming shoulders for this purpose, as well as serving to limit the upward movement of the short end of the frame against the arms 8 when the device is in an inactive position. 110

If desired there may be mounted upon the top of the frame 10 at the forward end thereof, a brush 32, the head thereof being carried upon an anchoring block 33 preferably of triangular cross section, with the hypotenuse of the triangle disposed to extend upwardly and forwardly, whereby the brush is supported in a forwardly inclined position. The block 33 may be suitably secured to the frame and as shown, is retained against the connecting or bight portion 11 125 130

and the sides of the frame, as by means of clips 34 apertured and engaged by screws 35 for securing the same to the block at the base thereof disposed toward the frame and 5 having curved jaw portions engaging the sides of the frame so as to detachably but rigidly secure the brush in position for use. It will also be understood that when the brush is in use, the frame will be folded 10 against the arms as when the device is in a position for wringing the mop cloth and may be held in this position by operating the wringing device so as to retain the mop cloth or strip under tension and preventing 15 the same from moving in angular relation to the arms and the handle while the brush is being used.

By means of the device described, the mop can be wrung or rinsed without the 20 necessity of dipping the hands in the water or wetting the hands, or subjecting the hands and wrists to strains incident to twisting a mop as is usually done. While I have shown and described the feed screw 25 as made up of two relatively stiff wire strands so as to produce a sharp pitch, it is to be understood that the screw may be of any well known or preferred form and consist of a bar cut to produce the spiral 30 grooves for engagement by the operating member 28. It will also be understood that while I have now illustrated what I consider to be the preferred embodiment of my invention, changes in the constructions, 35 arrangements, proportions and forms of the parts shown may be made so long as the same do not depart from the spirit and scope of the invention as claimed.

Having thus described the invention what 40 I claim is:—

1. A mop comprising a supporting member, arms carried by the supporting member, a frame pivoted to the arms, a mop cloth comprising a strip folded upon and beneath the frame, said frame being formed to prevent displacement of the strip, the extremities of the strip being disposed in contact, a feed screw carried by the supporting member and having one end thereof connected 45 to said extremities of the strip, and an operating member in the form of a nut engaged on the screw for movement longitudinally thereof to impart a revolving motion to the screw so as to twist the strip.

2. A mop of the class described comprising a handle, an attaching member at one end of the handle, arms rigid with said attaching member and spaced apart in parallel relation, said arms having outwardly directed extremities, a frame having side portions provided with pivot ears engaged on said outwardly directed extremities to pivotally support the frame, said frame having

a front cross member to receive in folded relation a mop cloth or strip with the free 65 ends thereof drawn taut around the rear end of the frame, means at the intermediate portion of the frame to hold said cloth or strip away from the sides of the frame whereby to prevent contact of the frame 70 with the surface cleaned, means for anchoring the ends of the mop cloth or strip, spaced brackets on the handle, a feed screw journaled in the brackets and held against longitudinal movement with respect to the 75 handle, the lower extremity of the screw being connected to the ends of the mop cloth, and an operating member in the form of an oscillating nut operatively engaged with the screw and whereby reverse 80 motion will be imparted to the screw for winding or unwinding the mop cloth or strip, as and for the purposes described.

3. A combined floor and wall mop comprising a handle, a mop supporting element 85 mounted at one end of the handle, a mop cloth having one end attached to said element, means carried by said element for engaging the mop cloth to hold the mop flat, a feed screw rotatably mounted along the 90 back of the handle and against downward movement, a clamp rigidly connected with the lower end of the feed screw and connecting the adjacent end of the mop cloth to the screw, and an operating nut mounted 95 on the screw and adapted upon being shifted thereon to impart a revolving motion to the screw for twisting and untwisting the mop cloth.

4. A combined floor and wall mop comprising a handle, a mop supporting element mounted at one end of the handle, a mop cloth having one end attached to said element, means carried by said element for engaging the mop cloth to hold the cloth flat, a feed screw rotatably mounted along the 100 back of the handle and held against downward movement, a clamp at the lower end of the feed screw for engaging the adjacent end of the mop cloth, an operating nut 105 mounted on the screw and adapted upon being shifted thereon to impart a revolving motion to the screw for twisting and untwisting the mop cloth, said mop supporting element being pivotally connected to the handle whereby the cloth is placed under tension when the element and operative portion of the cloth are disposed in a plane transversely of the handle and screw, said pivotal movement permitting said cloth 110 to hang loosely when movement is imparted to the nut, and means to limit the movement of the mop cloth supporting element toward the handle.

JOHN FRANCIS KELLY.
